UNITED STATES PATENT OFFICE.

ROBERT H. FORSYTH, OF WASHINGTON, DISTRICT OF COLUMBIA.

BOX FOR HOLDING COINS.

No. 810,742.

Specification of Letters Patent.

Patented Jan. 23, 1906.

Application filed July 28, 1905. Serial No. 271,649.

To all whom it may concern:

Be it known that I, ROBERT H. FORSYTH, of Washington, in the District of Columbia, have invented a new and useful Improvement 5 in Boxes for Holding Coins, of which the following is a specification.

This invention has reference to a fastening and sealing device for boxes which are employed more particularly for the storage of 10 coin in large quantities. Boxes for this purpose are constructed to receive a large number of coins arranged in a plurality of rows of columns or stacks, the box being formed with openings in its sides and ends, through which 15 the columns of coins may be viewed throughout their entire length, so that the absence of a coin will be instantly detected, the end openings in the box permitting of a view of the sides of four adjacent columns. In Let- 20 ters Patent of the United States No. 476,625, granted to me on the 7th day of June, 1892, a coin-box of this construction is disclosed, and it is to devices of this character that my 25 present invention is mainly directed, the aim being to provide a fastening and sealing device for securing the lid to the top of the box and for insuring detection in the event of an attempt to gain access to the contents.

With these ends in view my invention con- 30 sists of the improved fastening device which will be fully described in the specification and the novel features pointed out in the claims.

The invention consists also in providing the box with a division-plate to facilitate the 35 count of the coins, to take up lost space between the coins caused by wear, and to strengthen the box internally.

In the accompanying drawings, Figure 1 is a vertical sectional elevation through a coin- 40 box having my invention embodied therein, the section being taken on the line *a a* of Fig. 2. Fig. 2 is a top plan view of the same, showing the fastening device at the left sealed and that at the right as it appears before the sealing-disk is applied. Fig. 3 is a horizontal section on the line *b b* of Fig. 1. Fig. 4 is a perspective view of the fastening device with its several parts separated. Fig. 5 is a sectional elevation, on an enlarged 45 scale, of the sealing-head. Fig. 6 is a perspective view of the division-plate.

Referring to the drawings, 1 represents a box or receptacle of rectangular form comprising side walls 2, a bottom 3, and a removable top or lid 4, the bottom and lid constitut-

ing, in effect, the end walls of the box. The box is adapted to receive and hold a large number of coins, which are stacked therein in vertical columns 5 6 7 8, &c., arranged in rows side by side, the four adjacent columns 60 leaving between them a space or channel 9, extending throughout the length of the columns and of a general rectangular form in cross-section, the sides of said channel being formed by the curved sides of the four columns. In the present instance the box is of a form and size to accommodate ten columns or stacks arranged side by side in two rows of five columns each, so that there is presented between the stacks four channels or spaces, 70 opposite the ends of which spaces the top and bottom of the box are formed, respectively, with openings 10, 11, 12, 13, 14, 15, 16, and 17, preferably of circular form and of a size which will expose a portion of each of the end 75 coins of the four adjacent stacks. The purpose of this arrangement is that the openings in the top and bottom of the box shall expose a space between the four stacks bounded on its four sides by a portion of each of the sides 80 of the four columns, which space will present a general rectangular form with curved sides 18, 19, 20, and 21, with which space my improved fastening and sealing device is adapted to coöperate, as will now be de- 85 scribed. This device consists of a through-bolt A, adapted to be passed through the space between the columns and through the openings in the top and bottom of the box and serving to hold the top removably in 90 place, there being in the present instance two of these fastening-bolts, one at each end of the box. At one end the bolt has fixed to it a head B, formed with a squared shank *b* and with an annular flange *b'*, the squared shank 95 extending through the hole in the bottom of the box and into and fitting the rectangular space between the stacks of coins, while the annular flange *b'* extends outward and bears flatly against the bottom of the box. At its 100 opposite end the bolt is threaded, as at *a*², and has applied over its end a removable sealing-head C, formed with a squared shank *c*, extending through the opening in the top and fitting in the rectangular space between 105 the stacks and having a flange *c'* extending outward and bearing against the top. The sealing-head is formed with a cavity *c*², against the bottom of which a fastening-nut D, screwed on the threaded end of the bolt, 110

bears and by means of which nut the head C may be drawn tightly down on the lid, thereby holding the same firmly and rigidly against the top of the box.

5 The cavity in the sealing-nut is enlarged at its base and receives a sealing-disk E, of soft metal or analogous material, which after being seated in the cavity and on the nut is caused to tightly fill the former conveniently 10 by mashing the disk down by means of a punch, as indicated in dotted lines in Fig. 5.

By reason of the form of the sealing-cavity with its base enlarged, producing undercut sides, it will be seen that the sealing material 15 after being set cannot be removed bodily as a whole and again replaced. Hence any attempt to remove the lid to gain access to the coin will be indicated.

By providing the heads of the bolt with 20 squared or angular shanks fitting the angular spaces formed by the sides of the coin-stacks these heads are prevented from being turned, so that it is not possible to separate the parts of the fastening device by unscrewing them

25 without first removing the sealing-disk and exposing the fastening-nut D. These angular shanks thus constitute means coöperating with the coin-stacks for preventing the bolt or heads from being turned relatively to the 30 nut.

In order that the count of the coins in the box may be facilitated and any loss of space caused by wear on the sides of the coins be taken up, I provide a division-plate F, which 35 is inserted within the box, preferably midway of the height of the columns of coins and dividing them in two, with an equal number of coins in each division of the several columns. As shown more particularly in Fig. 40 6, this plate is rectangular in form and of a size which will exactly fit the interior of the box, being provided with openings f , f' , f'' , and f''' , corresponding in location and size with the openings through the top and bottom 45 of the box.

In filling the box after half the number of coins have been stacked therein the division-plate is placed on the top of the columns, after which the remainder of the coins are 50 stacked on top of the plate and the lid and fastening devices applied.

It frequently happens that the sides of coins, more particularly gold coins, become worn through frequent handling, and the aggregate wear of a large number will be quite noticeable. Inasmuch as the storing-boxes are of a size to hold a determinate number of coins of normal thickness, they will not in every case by reason of wear fill the box 55 60 tightly, as they should. By the provision of my division-plate the lost space between the coins is taken up and they are held tightly in the box and prevented from moving. Furthermore, the division-plate greatly strength-

ens the box by affording an internal support 65 midway between its ends.

Having thus described my invention, what I claim is—

1. In combination with a box or receptacle adapted to hold a plurality of stacks of coins, 70 a lid therefor, a fastening device for the lid adapted to extend in the space between the coin stacks, and means coöperating with the sides of the coin stacks for preventing the fastening device from turning. 75

2. In combination with a box adapted to hold stacks or columns of coins, a lid therefor, a fastening device for securing the lid in place, said fastening device adapted to extend in the space between the stacks of coin, 80 and a head on said fastening device adapted to fit in said space.

3. In combination with a box adapted to hold stacks of coins, a removable lid therefor, a fastening-bolt extending in the space 85 between the stacks of coins; and a head on the bolt formed with a shank fitting in the space between the coin stacks.

4. In combination with a box adapted to hold a plurality of stacks of coins and having 90 in its ends, openings in line with the space between the coin stacks, a fastening-bolt extending in said space, and heads on the ends of the bolt formed with shanks extending through the openings in the ends of the box 95 and fitting in the space between the coin stacks.

5. In combination with a box adapted to hold a plurality of stacks of coins, a removable lid therefor, the said lid and bottom of 100 the box being formed each with an opening in line with the space between the coin stacks, a bolt adapted to extend in said space, a head on one end of the same formed with a squared shank extending through the 105 opening in the bottom of the box, fitting in the space between the coin stacks and bearing against the outer side of the bottom, a removable head on the opposite end of the bolt, formed with a squared shank extending 110 through the opening in the lid and fitting in the space between the coin stacks; and a nut applied to the end of the bolt and serving to hold the parts together.

6. In combination with a coin-box adapted 115 to hold a plurality of stacks of coins, a removable lid therefor, a fastening-bolt adapted to extend in the space between the coin stacks, and a removable sealing-head for the bolt formed with an undercut cavity to receive a sealing medium, and having an opening through its bottom to receive the end of the bolt, said parts coöperating with the lid 120 and serving to retain the same in place.

7. In combination with a coin-box adapted 125 to hold a plurality of stacks of coins, a removable lid therefor, a fastening-bolt extending in the space between the coin stacks

and having its end threaded, a removable head adapted to be slipped over the threaded end of the bolt and formed with an angular shank fitting the space between the coin stacks, said head having a cavity to receive a sealing medium, and a fastening-nut screwed on the threaded end of the bolt within the cavity in the head.

8. In combination with a coin-box adapted to hold a plurality of stacks of coins, a removable lid therefor, a fastening-bolt extending in the space between the coin stacks, having one end threaded and having fixed to its opposite end a head formed with an angular shank fitting in the angular space between the coin stacks at one end, a removable head adapted to be slipped over the threaded end of the bolt and formed with an angular shank fitting the space between

the coin stacks, said head having a cavity to receive a sealing medium, and a fastening-nut screwed on the threaded end of the bolt and situated in the cavity in the head.

9. In combination with a box adapted to hold a plurality of stacks of coins, and formed in its top and bottom with openings in line with the space between the coin stacks, a division-plate fitting within the box and dividing the coin stacks and formed with openings in line with the space between the coin stacks.

In testimony whereof I hereunto set my hand, this 22d day of July, 1905, in the presence of two attesting witnesses.

ROBERT H. FORSYTH.
